UNITED STATES PATENT OFFICE

138,650

DESIGN FOR A BUILDING

Roy C. Keeth, McPherson, Kans.

Application April 3, 1944, Serial No. 113,128

Term of patent 14 years

(Cl. D13—1)

To all whom it may concern:

Be it known that I, Roy C. Keeth, a citizen of the United States, residing at McPherson, in the county of McPherson and State of Kansas, have invented a new, original, and ornamental Design for a Building, of which the following is a specification, reference being had to the accompanying drawing, forming part thereof.

Figure 1 is a front elevational view of a building, showing my new design.

Figure 2 is a plan view of the building.

The rear wall of the building has windows and a door similar to the front view. The ends of the building are plain.

I claim:

The ornamental design for a building, as shown and described.

ROY C. KEETH.
